ABSTRACT OF THE DISCLOSURE

This disclosure relates to an expandable mandrel for carrying a tubular core wherein such mandrel has a supporting member provided with a plurality of symmetrically arranged keyway means each having inclined planar bearing surface means and each carrying an associated tapered key which has a cylindrical core carrying segment fastened thereto. The plurality of cylindrical segments are normally held in a retracted, i.e. reduced diameter, position by yieldable urging means which acts axially along the elongated axis of such supporting member and holding means which acts radially inwardly toward such axis. Both the urging means and holding means are overridden to move the core carrying segments radially outwardly into engagement with the inside surface means of such tubular core upon driving such mandrel with a suitable drive means.

This invention pertains to a core carrying mandrel and more particularly to an expandable mandrel for carrying a tubular core.

It has been previously proposed in copending patent application, Ser. No. 475,218, filed July 27, 1965, to provide a mandrel adapted to be used with a strip conductor coil making apparatus. Such previously provided mandrel is constructed and arranged so that it is insertable within a tubular core and then expanded to firmly hold such core in position during a subsequent operation wherein a strip conductor is wound on the core carried by such mandrel. The previously provided mandrel is comparatively expensive to produce and does not exert holding forces which are uniformly applied in all directions against inside surface means of an associated tubular core.

Accordingly, it is a feature of this invention to provide an improved expandable mandrel which is of simple and economical construction.

Another feature of this invention is to provide an improved expandable mandrel of the character mentioned which provides holding forces which are more uniformly applied in a radial manner against inside surface means of a tubular core to be supported thereon.

Therefore, it is an object of this invention to provide an improved expandable mandrel having one or more of the novel features of this invention as set forth above or hereinafter shown or described.

Other objects, uses, and advantages of this invention are apparent from a reading of this description which proceeds with reference to the accompanying drawings forming a part thereof and wherein:

FIGURE 1 is a side view of the improved expandable mandrel of this invention and showing by dotted lines the position of a tubular core to be carried thereon.

FIGURE 2 is an exploded perspective view particularly illustrating the construction and arrangement of the co-

2

operating members which comprise the expandable portion of the mandrel of FIGURE 1.

FIGURE 3 is a view on the line 3—3 of FIGURE 1.

FIGURE 4 is a sectional view on the line 4—4 of FIGURE 3.

While the various features of this invention are herein-after illustrated and described as being particularly adaptable for providing an expandable mandrel adapted to be used with a strip conductor coil winding apparatus, or the like, it is to be understood that the various features of this invention can be utilized singly or in any combination thereof to provide an expandable mandrel for other uses, as desired.

Therefore, this invention is not to be limited to only the embodiment illustrated in the drawings, because the drawings are merely utilized to illustrate one of the wide variety of uses of this invention.

In the exemplary embodiment of this invention illustrated in the drawings an expandable mandrel designated generally by the numeral 20 is illustrated. Mandrel 20 is suitably mounted for essentially frictionless rotation on a right circular cylindrical rod end portion 21 of a supporting member 22.

Mandrel 20 has a freely rotatable support assembly 24 designated generally by the numeral 24 and comprising a cylindrical member 25 having a threaded outer surface shown at 26 and a central bore 27 which defines a blind hole in one end thereof. Support assembly 24 also has a sleeve-like member 30 which is provided with threads 31 at its inner end which are threadedly engaged with threads 26 of member 25 to hold members 25 and 30 firmly fastened together.

Bearing means shown as a pair of spaced apart ball bearings, or the like, each designated by the numeral 32 are provided at the terminal end of rod end 21 in spaced apart relation. Bearings 32 support assembly 24 and hence mandrel 20 essentially in a cantilevered manner on rod end 21.

Bearings 32 are inserted in central bore 27 and the inner bearing 32 is positioned with its outer race against an annular shoulder 25A in member 25 and its inner race against a cap-like member 21A fastened at the terminal end of rod end 21. Bearings 32 are held in spaced apart relation in any suitable manner and in this example a cylindrical sleeve 33 is placed therebetween and in surrounding relation around rod end 21.

A split ring 34, commonly referred to as a snap ring, is installed in a cooperating annular groove 34A provided in member 25. Another snap ring 38, or the like, is installed in a cooperating annular groove 38A in rod end 21. Snap rings 34 and 38 are used to prevent relative axial movement between rod end 21 and support assembly 24 with bearings 32 installed in position.

Thus, it is seen that support assembly 24 and hence mandrel 20 is free to rotate in a frictionless manner on bearings 32 while being securely held in position at the end of member 22.

However, it will be appreciated that other techniques may be used to hold mandrel 20 cantilevered on member 22 while enabling free rotation thereof yet preventing relative axial movement therebetween. For example, bearings 32 may be suitably pressed or otherwise fixed on rod end 21 and used together with snap ring 34 and shoulder 25A to prevent axial movement of member 22 relative to support assembly 24, if desired.

The outer end portion of mandrel 20 is radially expandable and such radially expandable portion is supported on rotatable support 24 and is adapted to engage inside surface means of a tubular core to be carried thereon in a manner as will be described in detail subsequently.

The outer end portion of mandrel 20 comprises a supporting member designated by the numeral 35 which has an elongated central axis designated by the numeral at 36. Member 35 has a rod-like portion 37 comprising its terminal inner end which is fixed to rotatable support assembly 24 so that supporting member 35 and the members carried thereon are freely rotatable with rotatable support assembly 24.

Rod-like portion 37 is fixed to rotatable support 24 by being fixed to a central extension 40 of member 25. Extension 40 is substantially cylindrical in peripheral outline and has a substantially cylindrical recess 41 in its terminal end which is adapted to receive the terminal inner end 42 of rod-like portion 37 therewithin. Terminal inner end 42 is fastened to cylindrical end portion 40 in a fixed manner by use of a threaded set screw 43, or the like.

Member 35 has a circular cross section with respect to any section taken perpendicular to axis 36 and in this example of the invention member 35 is preferably substantially frusto-conical in outer peripheral configuration. Member 35 also has a plurality of inclined keyway means or keyways each designated generally by the numeral 45 and in this example of the invention three of such inclined keyways are formed in frusto-conical member 35 in a symmetrical manner about axis 36 and spaced apart 120 degrees from each other.

Each keyway 45 has planar inclined bearing surface means or an inclined bearing surface designated by the numeral 46. Inclined planar bearing surfaces 46 are arranged on frusto-conical member 35 at an acute angle 35 with respect to axis 36.

Mandrel 20 has a plurality of three identical core support means each designated generally by the numeral 49 and each carried along an associated keyway 45. In particular each core support means is slidably carried along an associated inclined planar bearing surface 46. Each core support means 49 comprises a substantially cylindrical segment 50 which is suitably fastened to an associated tapered member or key 51.

Each tapered member or key 51 is substantially trapezoidal in cross section, see FIGURE 2, and is adapted to be placed within an associated keyway 45 so that its bottom surface designated by the numeral 52 engages and is supported on an associated planar surface 46 of a keyway 45. Each tapered key 51 has fastening means shown as a threaded bolt 54 which extends through an opening 55 in tapered key 51 and is threaded in a cooperating threaded opening 56 of an associated cylindrical segment 50.

Each key 51 has a counterbore 60 arranged concentrically about bore 55 for receiving the head 61 of an associated bolt 54 so that each assembly 49 comprising a tapered key 51 and a cylindrical segment 50 fastened thereto may be moved along a supporting keyway 45 so that bolt 54 does not obstruct the sliding movement.

Thus, it is seen that a plurality of three tapered keys 51 and associated cylindrical segments 50 are provided about the periphery of frusto-conical member 35 so as to provide a substantially continuous cylindrical outside surface which is adapted to engage inside surface means of an associated tubular core designated by the numeral 63 and shown by dotted lines in the drawings. In this example, tubular core is shown as being substantially right circular cylindrical outline having corresponding cylindrical inside surface means designated by the numeral 64.

Each cylindrical segment 50 has cooperating groove means or a groove designated by the numeral 65 which extends radially inwardly from its outer periphery. Each groove 65 is provided in an associated cylindrical segment 50 so that upon fixing each segment 50 on its associated tapered key 51 and placing the resulting core support as-

sembly 49 in position about the periphery of member 35 grooves 65 are placed in aligned relation so as to define a substantially continuous annular groove.

Holding means comprising ring means shown as a ring-like member 66 made of a stretchable rubber-like material is nested within aligned grooves 65 and holds cylindrical segments 60 and hence support assemblies 49 radially inwardly by urging such members toward axis 36 of member 35. With rubber-like ring 66 in position in its associated grooves 65 one component of the radial force urging each assembly 49 against its associated inclined surface 46 tends to urge such assembly toward the terminal outer end of mandrel 20.

Mandrel 20 has stop means provided therein and in this example of the invention such stop means is provided as an integral part of supporting member 35 and comprises the terminal end face or surface designated by the numeral 70 and defining the forward end of each keyway 45. Each surface 70 is adapted to receive the terminal outer end of tapered key 51 thereagainst and prevent each key 51 with its fastened cylindrical segment 50 from being moved axially outwardly beyond stop 70.

Mandrel 20 also has urging means yieldingly urging the three core support means 49 against stops 70. The urging means in this example of the invention comprises a compression spring 72 and a circular plate 73. Compression spring 72 is adapted to be placed in surrounding relation concentrically about inner rod-like end portion 37 of frusto-conical member 35 and circular plate has an opening 74 therein so that it can be slid around end portion 37.

Spring 72 acts between the face 75 of cylindrical end 40 and plate 73 so as to urge plate 73 outwardly, to the left as viewed in FIGURE 4. Plate 73 engages cylindrical segments 50 and keys 51 and pushes such segments and keys outwardly against stops 70.

The urging means comprised of spring 72 and circular plate 73 urge the core support means 49 outwardly to a disengaged position which is illustrated in FIGURE 4 of the drawings. At such disengaged position the core support means 49 cooperate to define a first substantially cylindrical surface having a comparatively small first diameter. The core support means 49 are adapted to be engaged and pushed inwardly, to the right as viewed in FIGURE 4, so as to cause each key 51 to ride along its inclined planar surface 46 and thereby radially expand the core support means 49 so that at an inward position such core support means cooperate to define a second substantially cylindrical surface which has a second diameter which is larger than the first diameter defined at the disengaged position and such second cylindrical surface is particularly adapted to engage and support inside surface means 64 of core 63.

Mandrel 20 has means for engaging inside surface means of tubular core 63 to provide interim holding of such tubular core during those time intervals where core 63 must be held on mandrel 20 and the core support means 49 have not been brought into engagement therewith. In this example of the invention such interim holding means comprises ball plunger means shown as a plurality of ball plunger assemblies 77 each having a ball 80 which is normally urged outwardly by a compression spring 81. Ball plunger assemblies 77 enable tubular core 63 to be held on mandrel 20 for the time interval that such tubular core is picked up from an associated supply bin of a strip coil winding machine, for example, and indexed into position for winding a strip conductor coil thereon.

The improved mandrel 20 of this invention has driven means provided on frusto-conical member 35 which is adapted for connection with a suitable drive means. The driven means of this exemplary embodiment comprises a clutch face 84 provided at the terminal end of member 35. Clutch face 84 is preferably formed as an integral part of member 35 and thereby substantially reduces the cost of the overall mandrel in that it is not necessary to

provide a separate cooperating part which must be separately made and assembled in position at considerably greater cost.

Mandrel 20 is driven by any suitable standard drive means and such drive means has a cooperating drive face or drive clutch means which corresponds to and is adapted to be brought into engagement with clutch means 84 to rotatably drive mandrel 20.

The operation of mandrel 20 is such that as the drive means comes into engagement with the integral clutch face 84 tubular core 63 is pushed inwardly, to the right as seen in FIGURE 4, over interim holding assemblies 77 and against a stop shown as a shoulder 85 provided around the outer end of cylindrical member 30 comprising assembly 24. As core 63 is pushed over holding assemblies 77 against stop 85 a portion of the drive means engages the terminal outer face of the three core support means 49 so as to axially move such core support means 49 along frusto-conical member 35 while overriding the action of both the urging means or spring 72 and the yielding holding means or rubber-like O-ring 66.

The core support means 49 are preferably engaged and pushed inwardly by the above mentioned drive means in a known manner and such support means are also held at such inward position by such drive means. The inward movement of core support means 49 causes radial expansion thereof, as previously described, into engagement with inside surface 64 of tubular member 63. The unique construction of mandrel 20 enables each core support means 49 to exert a substantially uniform holding force about the periphery of inside surface 64.

The friction surface area 46 provided by each keyway 45 is comparatively small, much smaller than the equivalent surface area of previous devices, and together with the guiding of support means 49 along each keyway 45 assures that only a small amount of force is required to urge each core support means 49 axially inwardly and simultaneously radially outwardly along its associated ramp surface 46. Further, the movement provided is very smooth without sticking tendencies and hence assures that all core support means 49 move substantially simultaneously to provide the above mentioned uniform clamping force.

The construction and arrangement of the various component parts of mandrel 20 is such that mandrel 20 is easily manufactured and assembled without requiring special equipment. In particular the key operating components of mandrel 20 are very inexpensively produced.

Thus, the tapered keys 51 may be economically produced from rectangular bar stock. Similarly, the cylindrical segments 50 may be produced from right circular cylindrical members having the desired wall thickness and merely cut as required. The keyways 45 may also be formed in any number of inexpensive ways one of which would be to use a milling cutter to cut each keyway in frusto-conical member 35.

Likewise, the provision of driven means 84 is simply provided by the cutting of two V-shaped cuts taken in the terminal end of member 35 so as to diametrically intersect each other while being angularly spaced 90 degrees from each other.

The various component parts of mandrel 20 may be made of any suitable material. However, each cylindrical segment or member 50 is preferably made of plastic, steel, or the like. Also, each tapered key is preferably made of brass. In addition, suitable surface treatment means may be utilized to reduce sliding friction wherever applicable.

Member 35 in this exemplary embodiment of the invention is shown as a frusto-conical member and is preferably made of hardened steel. However, member 35 may be made of any suitable material.

The outer portion of member 35 which has keyways 45 provided therein is shown as a frusto-conical member. Nevertheless, such outer peripheral configuration of mem-

ber 35 may be of other shapes. For example, member 35 may be a cylindrical member which has inclined keyways 45 provided therein spaced 120 degrees apart from each other in the manner illustrated so that such keyways gradually converge toward the outer end of mandrel 20 and, in effect, define three planar surfaces which are identical in position and arrangement to planar surfaces 46 and provide the same action. Thus, by making member 35 of cylindrical or other inexpensive configuration and providing keyways 45 therein substantially identical in size and symmetrical arrangement to keyways 45 provided in member 35 the cost of mandrel can be further reduced.

Terms such as "outwardly," "inwardly," "outer," "inner," "side," "end," "forward," "right," "left," and the like have been used in this disclosure of the invention merely for ease of description and to correspond with the arrangement of component parts as illustrated in the drawings and such terms should not be considered as limiting the scope of this invention in any way.

Thus, it is seen that an improved expandable mandrel has been provided by this invention which is of simple and economical construction and which holds an associated tubular core in a more uniform manner.

While the form of the invention now preferred has been disclosed as required by statute, other forms may be used, all coming within the scope of the claimed subject matter which follows.

What is claimed is:

1. An expandable mandrel for carrying a tubular core comprising, a supporting member having an elongated central axis and an outer end portion which has a substantially frusto-conical configuration, driven means on said supporting member for connection with a drive means said driven means comprising a toothed clutch face defined by substantially V-shaped cutouts in the terminal small diameter and of said frusto-conical member, a plurality of planar inclined bearing surface means symmetrically arranged on said frusto-conical portion of said supporting member and arranged at an acute angle with respect to said axis, and a plurality of core support means corresponding in number to said plurality of inclined bearing surface means and being yieldably held against said frusto-conical portion, said core support means being engaged and axially moved along said bearing surface means to cause a radial movement thereof into engagement with inside surface means of said tubular core upon engaging said driven means with said drive means and said support means exerting a substantially uniform holding force against said inside surface means following said radial movement.

2. An expandable mandrel for carrying a tubular core comprising, a supporting member having an elongated central axis, driven means on said supporting member for connection with a drive means, a plurality of planar inclined bearing surface means symmetrically arranged on said supporting member and arranged at an acute angle with respect to said axis, and a plurality of core support means corresponding in number to said plurality of inclined bearing surface means, each core support means comprising a tapered member slidably engaging and carried on an associated bearing surface means and comprising a substantially cylindrical segment fastened to each tapered member, said core support means being engaged and axially moved along said bearing surface means to cause a radial movement thereof and engagement of said segments with inside surface means of said tubular core upon engaging said driven means with said drive means and said segments exerting a substantially uniform holding force against said inside surface means following said radial movement.

3. An expandable mandrel for carrying a tubular core comprising, a supporting member having an elongated central axis, driven means on said supporting member for connection with a drive means, a plurality of planar in-

clined bearing surface means symmetrically arranged on said supporting member and arranged at an acute angle with respect to said axis, and a plurality of core support means corresponding in number to said plurality of inclined bearing surface means, each core support means comprising a tapered member slidably engaging and carried on an associated bearing surface means and comprising a substantially cylindrical segment fastened to each tapered member, said core support means being engaged and axially moved along said bearing surface means to cause a radial movement thereof and engagement of said segments with inside surface means of said tubular core upon engaging said driven means with said drive means and said segments exerting a substantially uniform holding force against said inside surface means following said radial movement, and said mandrel further comprising ball plunger means for engaging inside surface means of said tubular core to provide interim holding of said tubular core while it is disengaged from said core support means.

4. An expendable mandrel for carrying a tubular core comprising, a supporting member having an elongated central axis, driven means on said supporting member for connection with a drive means, a plurality of planar inclined bearing surface means symmetrically arranged on said supporting member and arranged at an acute angle with respect to said axis, and a plurality of core support means corresponding in number of said plurality of inclined bearing surface means, each core support means comprising a tapered member slidably engaging and carried on an associated bearing surface means and comprising a substantially cylindrical segment fastened to each tapered member, said core support means being engaged and axially moved along said bearing surface means to cause a radial movement thereof and engagement of said segments with inside surface means of said tubular core upon engaging said driven means with said drive means and said segments exerting a substantially uniform holding force against said inside surface means following said radial movement, and said mandrel further comprising stop means on said supporting member for each of said core support means, said stop means being formed as an integral part of said supporting member adjacent said driven means, and urging means yieldingly urging said core support means outwardly against said stop means such that the outer periphery of said core support means defines a first substantially cylindrical surface having a comparatively small first diameter, whereby upon engaging and axially moving said core support means along said bearing surface means said urging means is overridden to cause said radial movement of said core support means outwardly to define a second substantially cylindrical surface having a second diameter larger than said first diameter.

5. An expendable mandrel for carrying a tubular core comprising, a supporting member having an elongated central axis, driven means on said supporting member for connection with a drive means, a plurality of planar inclined bearing surface means symmetrically arranged on said supporting member and arranged at an acute angle with respect to said axis, and a plurality of core support means corresponding in number of said plurality of inclined bearing surface means, each core support means comprising a tapered member slidably engaging and carried on an associated bearing surface means and comprising a substantially cylindrical segment fastened to each tapered member, said core support means being engaged and axially moved along said bearing surface means to cause a radial movement thereof and engagement of said segments with inside surface means of said tubular core upon engaging said driven means with said drive means and said segments exerting a substantially uniform holding force against said inside surface means following said radial movement, and said mandrel further comprising holding means for yieldingly radially holding

5 said core support means against said supporting member, stop means on said supporting member for each of said core support means, said stop means being formed as an integral part of said supporting member adjacent said driven means, and urging means yieldingly urging said core support means outwardly against said stop means such that the outer periphery of said core support means defines a first substantially cylindrical surface having a comparatively small first diameter, whereby upon engaging and axially moving said core support means along said bearing surface means said urging means and holding means are overridden to cause said radial movement of said core support means outwardly to define a second substantially cylindrical surface having a second diameter larger than said first diameter.

10 6. An expandable mandrel for carrying a tubular core comprising, a supporting member having an elongated central axis, driven means on said supporting member for connection with a drive means, a plurality of substantially identical inclined keyway means symmetrically arranged on said supporting member and each having planar inclined bearing surface means and being arranged at an acute angle with respect to said axis, a plurality of core support means corresponding in number to said plurality of keyway means, each core support means comprising a tapered key slidably engaging and carried on an associated bearing surface means and comprising a substantially cylindrical segment fastened to each tapered key, said tapered keys providing a comparatively small 15 friction surface enabling easy sliding of said core support means into a core supporting position, and urging means yieldingly urging said core support means outwardly to a disengaged position, said core support means being engaged and axially moved inwardly along said keyway means to cause an outward radial movement thereof into engagement with inside surface means of said tubular core upon engaging said driven means with said drive means and said core support means exerting a substantially uniform holding force against said inside surface means following said outward radial movement.

20 7. An expandable mandrel for carrying a tubular core comprising, a supporting member having an elongated central axis, driven means on said supporting member for connection with a drive means, a plurality of substantially identical inclined keyway means symmetrically arranged on said supporting member and each having planar inclined bearing surface means and being arranged at an acute angle with respect to said axis, a plurality of core support means corresponding in number to said plurality of keyway means, each core support means comprising a tapered key slidably engaging and carried on an associated bearing surface means and comprising a substantially cylindrical segment fastened to each tapered key, said tapered keys providing a comparatively small 25 friction surface enabling easy sliding of said core support means into a core supporting position, and urging means yieldingly urging said core support means outwardly to a disengaged position, said core support means being engaged and axially moved inwardly along said keyway means to cause an outward radial movement thereof into engagement with inside surface means of said tubular core upon engaging said driven means with said drive means and said core support means exerting a substantially uniform holding force against said inside surface means following said outward radial movement, and said mandrel further comprising stop means on said supporting member for each of said core support means, said stop means being formed as an integral part of said supporting member adjacent said driven means, and said urging means yieldingly urging said core support means outwardly against said stop means to define said disengaged position.

30 8. A mandrel as set forth in claim 7 further comprising ball plunger means for engaging inside surface means of said tubular core to provide interim holding of said

tubular core while it is disengaged from said core support means.

9. A mandrel as set forth in claim 7 in which the outer end portion of said supporting member is of circular cross section and said keyway means are provided in

5

said outer end portion.

10. A mandrel as set forth in claim 9 in which said supporting member has an inner rod-like portion which has its terminal inner end fixed to a freely rotatably sup-

10

port therefor and said urging means comprises compres-

sion spring means acting between said rotatable support and said core support means.
